UNITED STATES PATENT OFFICE.

WALTER M. CONGER, OF NEWARK, NEW JERSEY.

IMPROVEMENT IN COAL-HOD STANDS.

Specification forming part of Letters Patent No. 126,676, dated May 14, 1872.

Specification describing a certain new and useful household article, which I term a Coal-Hod Stand, invented by me, WALTER M. CONGER, of Newark, Essex county, New Jersey.

The object of my invention is to provide a suitable stand for a coal-hod, which will prevent the soiling of the floor or carpet.

The following is a description of what I consider the best means of carrying out the invention.

The accompanying drawing forms a part of this specification. Figure 1 is a plan view, and Fig. 2 is a cross-section of the completed article.

Similar letters of reference indicate like parts in both the figures.

The article is manufactured from a single piece of tough sheet-iron struck up into form at one or more operations with suitable dies. I will designate the several parts by A¹ A², &c. A¹ is a broad plane base. A² is a rim surrounding the part A¹, and rising with tasteful beads or partial convolutions to an upper edge or principal bead elevated one inch, more or less, above the base. A³ is a drooping lip outside of the rim proper, A², and descending from the upper edge or principal bead to a point a little below the base A¹. The lower edge of the lip A³ is finished by being rolled under. There may be a wire in the edge or not, as preferred. The whole may be richly japanned or otherwise protected, and variously decorated, especially on the outer surface of the hanging

lip A³. I propose to cover the upper surface of the plain portion A¹ with a layer of leather, parchment, cartridge or other paper, papier-maché, cloth, felt, wood, cork, India rubber, kaptulicon, matting, netting, or analogous soft material. Such material may be permanently fixed to the iron by cementing with glue, in which a little acetic acid or vinegar has been mingled, or by other suitable cement adapted to adhere strongly to the surface of iron; or it may lie loosely therein, and may be capable of being frequently exchanged and cleaned.

It is not absolutely essential that the hanging portion A³ be continuous, as it may be perforated in various ways. So, also, it may be of brass or other metal, nickel-plated or otherwise coated. I greatly prefer, however, for lightness and economy, as also for general usefulness, that it shall be rolled iron, with not only the base A¹ and rim proper, A², but also the hanging and bracing portion A³ in a continuous piece:

I claim—

As a new article of manufacture, the coal-hod stand, constructed as herein described, and adapted to serve as specified.

In testimony whereof I have hereunto set my hand this 26th day of February, 1872, in the presence of two subscribing witnesses.

WALTER M. CONGER.

Witnesses:

THOMAS D. STETSON,
ARNOLD HORMANN.
